UNITED STATES PATENT OFFICE.

WILLIAM M. MITCHELL, OF LOUISVILLE, KENTUCKY.

RAIL-ANCHOR

1,184,478.

Specification of Letters Patent. Patented May 23, 1916.

Application filed March 6, 1916. Serial No. 82,474.

To all whom it may concern:

Be it known that I, WILLIAM M. MITCHELL, a citizen of the United States, residing at Louisville, county of Jefferson, and State of Kentucky, have invented certain new and useful Improvements in Rail-Anchors, of which I do declare the following to be a full, clear, and exact description, reference being had to the accompanying drawings, forming a part of this specification.

My present invention has for its object to provide a simple and efficient construction of rail anchor designed to prevent the creeping of the rails of railway tracks and the invention consists in the features of improvement hereinafter described, illustrated in the accompanying drawings and particularly defined in the claims at the end of this specification.

By the term rail anchor, as here employed I wish to have it understood as including not merely devices designed to prevent the creeping of the rails but including also such devices as anti-creeper tie plates" which perform not only the function of anti-creeper anchors but the additional function of supporting the base of the rail upon the tie.

Figure 1 is a plan view of a rail anchor embodying my invention, a portion of a railway rail and of a track tie being also shown. Fig. 2 is a view in cross section on line $\alpha-\alpha$ of Fig. 1. Fig. 3 is an end view of the rail anchor, the tie being shown in section on line $3-3$ of Fig. 1. Fig. 4 is a view in cross section on line $4-4$ of Fig. 2, a portion of a railway rail being shown at the right hand side of this figure. Fig. 5 is a front view of the end portion of the anchor having the abutment and the locking jaw. Fig. 6 is a view similar to Fig. 2, but showing a modified form of the invention. Fig. 7 is a view in end elevation of the modified form of the invention shown in Fig. 6. Fig. 8 is a view similar to Fig. 1 but showing an embodiment of my invention as applied to an anti-creeper tie plate. Fig. 9 is a view on line $9-9$ of Fig. 8. Fig. 10 is a view on line $10-10$ of Fig. 9, the locking jaw, being omitted.

In the accompanying drawings A designates a railway rail and B designates a railway tie adjacent to which my improved rail anchor is shown.

Referring to the form of the invention shown on Sheets 1 and 2 of the drawings, the

body portion of my improved anchor comprises a member C adapted to extend across and beneath the base flanges α and α' of the rail A. At one end of the member C there is formed a suitable jaw C' that is shown as formed integral with the member C and provided with a slot c adapted to receive the base flange α of the rail. The upper portion of the member C is arranged to bear against the lower surface of the base of the rail and at the side of the member C farthest from the fixed jaw C' is formed a shoulder c' adapted to bear against the outer edge of the base flange α' of the rail. Upon the end of the member C and outside the shoulder c' is formed a rib C² having an expanded head c² adapted to fit within a corresponding groove formed within a locking jaw D that is movably mounted upon said rib.

By reference to Figs. 1 and 3 of the drawings it will be seen that the end of the member C, that carries the locking jaw D is extended transversely and is provided with a downwardly extending abutment C³ adapted to bear against the railway tie B when the anchor is in position for use.

In the form of my invention illustrated in Figs. 1 to 7 of the drawings, the upper surface of the end of the member C that carries the locking jaw D is provided outside the rib C² with a series of serrations or teeth c⁴ adapted to be engaged by a corresponding series of teeth or serrations d that are formed upon the under side of the outer portion of the locking jaw D, these teeth or serrations c⁴ and d, by their inter-engagement, serving to hold the locking jaw securely in position and against accidental displacement when the locking jaw has been placed in position for use, as will hereinafter more fully appear.

By reference to Fig. 1 of the drawings, it will be seen that the shoulder c' is arranged transversely of the member C and parallel to the line of the outer edge of the rail base flange α' , and in the preferred embodiment of my invention the rib C² is inclined toward the shoulder c', this inclination of the rib C² serving to cause the locking jaw D to move inward toward the base flange of the rail as the jaw is forced to position to clamp and hold the flange of the rail. So also, by reference to Figs. 3 and 4 of the drawings, it will be seen that the rib C² of the member C is inclined downwardly toward the abutment C³, so that as the jaw D is placed

in position for use it will also be moved downwardly into firm bearing against the upper inclined surface of the base flange a' of the rail. In other words, the shape and arrangement of the rib C^2 is such that as the locking jaw is forced to position for use it will move both downwardly and inwardly toward the base flange a' of the rail and thus secure a most effective grip upon the rail base, this grip being tightened as the rail A tends to creep in the direction of the arrow, Fig. 1 of the drawings.

The relative sizes of the rib C^2 and of the groove formed within the locking jaw D are such that the jaw will slip freely and somewhat loosely upon the rib C^2 ; and as the locking jaw D is passed over the end of the rib C^2 farthest from the abutment C^3 , and is moved toward the abutment, the serrated outer lower portion of the jaw will at first ride over the serration c^4 , but as the inner portion d' of the jaw engages and bears upon the base flange a' of the rail, the jaw D will rock slightly in the direction of the arrow, Fig. 2, so as to cause its serrations or teeth d to securely interlock with the serrations or teeth c^4 at the outer end of the member C.

In applying my improved rail anchor to a rail, the member C will be passed beneath the rail and the jaw C' will be tightly forced over the base flange a of the rail and the shoulder c' at the opposite end of the member C of the anchor will be brought to bear against the edge of the flange a' of the rail. The locking jaw D will then be slipped over the end of the rib C^2 farthest from the abutment C^3 and will be forced toward the abutment, the shape and arrangement of the rib C^2 causing the locking jaw, as it is thus placed in position for use, to move inward and downward toward the base flange a' until the inner portion d' of the locking jaw D is in firm engagement with the upper surface of the base flange a' . When the locking jaw D is thus forced into firm bearing against the rail flange a' , the interlocking serrations or teeth d and c^4 will serve to securely hold the locking jaw in position. By reference more particularly to Fig. 4 of the drawings, it will be seen that the shoulder c' tapers downwardly toward the abutment C^3 of the member C, thus permitting the locking jaw to move downward as it is forced to position for use.

In Figs. 6 and 7 of the drawings I have shown a slightly modified form of the invention, in which the locking jaw D is formed with serrations or teeth d^5 located within the groove of the jaw, these serrations or teeth d^5 being adapted to engage with corresponding serrations or teeth c^5 that are formed upon the rib C^2 . When the serrations are thus formed upon the jaw and rib respectively, the serrations c^5 and d^5

hereinbefore described, may be omitted or they can also be used if desired. When the serrations d^5 and c^5 are used, the transverse dimension of the groove in the locking jaw D will be somewhat greater than in the form of the invention hereinbefore described. With this modified form of the invention, it will be seen that as the locking jaw D is forced to position for use, and is necessarily slightly turned in the direction of the arrow, Fig. 6, the lower portion of the jaw D will act as a fulcrum so that the upward pressure on the jaw will tend to force teeth d^5 into engagement with the teeth c^5 on the outer side of the rib C^2 .

It will be seen that when my improved rail anchor is applied to a rail, the shoulder c' will afford an effective bearing and grip upon the edge of the base flange a' of the rail while the opposite base flange is engaged by the jaw C', and the locking jaw D will serve to firmly maintain the shoulder c' in engagement with the base flange a' while the jaw D effectively grips the upper surface of the flange a' .

My present invention is adapted for use upon rails of different weights and sizes and if the base of the rail be so narrow that the outer edge of the flange a' does not initially bear against the shoulder c' , this bearing will occur as soon as a slight rocking action or shackle action of the anchor occurs incident to the bearing of the abutment C^3 against the tie B.

On Sheet 3 of the drawings I have shown my invention applied in modified form to an anti-creeper tie plate. In this form of invention C^5 designates the body or main member of the tie plate that is provided with suitable holes c^7 by which the plate may be spiked to the tie. At one end of the body member C^5 is formed a rigid jaw C^6 adapted to engage the base flange a of the rail A. Upon the upper surface of the body member C^5 adjacent the opposite end thereof is formed a shoulder c' corresponding to the shoulder c' in the form of the invention hereinbefore described, and adapted to bear against the outer edge of the base flange a' of the rail. Adjacent the shoulder c' there are formed on the body member C^5 raised ribs C^9 and C^{10} that preferably meet at the center of the body member C^5 . The contour of each of these ribs C^9 and C^{10} is preferably the same as of the rib C^2 hereinbefore described, and each of these ribs C^9 and C^{10} is adapted to receive a locking jaw D^4 corresponding in function to the locking jaw D hereinbefore described and having formed therein a downwardly open groove to receive the rib upon which it is mounted. In this form of my invention I have shown each of the locking jaws as provided at its outer side with laterally projecting portions or tongues d^7 adapted to enter depressions or serrations c^8

*c*⁸ formed in the upper surface of the body member *C*⁵. Preferably, these serrations or depressions *c*⁸ are inclined, as shown in Fig. 9, to permit the portions or tongues *d*⁷ to be readily bent into the depressions *d*⁸ when the locking jaws *D*⁴ have been securely forced to position for gripping the rail, as indicated in Figs. 8 and 9 of the drawings. In this form of my invention, as in that hereinbefore described, the ribs *C*⁹ and *C*¹⁰ are inclined both in vertical and horizontal direction so that as the locking jaws *D*⁴ are forced in position for use, they will move inward and downward toward the base flange *a*' of the rail.

In the form of my invention last described, in which the anchor is provided with two ribs oppositely inclined, the creeping of the railway rail in either or both directions will be effectively prevented; and when the locking jaws are in position for use and the tongues or lateral projections *d*⁷ are hammered down into the seats or depressions *c*⁸ of the body member *C*⁵, all danger of the accidental loosening of the locking jaws *D*⁴ will be avoided.

I wish it distinctly understood that the details of construction above set out may be varied without departing from the scope of the invention and that features of the invention may be employed without its adoption as an entirety.

Having thus described my invention what I claim as new and desire to secure by Letters Patent, is:—

1. A rail anchor comprising a member adapted to extend beneath the base of a rail and jaws at the ends of said member for retaining said member on the rail, one of said jaws being a wedging jaw transversely movable upon said member, said member being provided with a shoulder adjacent one end to engage the outer adjacent edge of the base flange of the rail.

2. A rail anchor comprising a member adapted to extend beneath the base of a rail and jaws at the ends of the member for retaining said member on the base flanges of the rail, one of said jaws being movable upon said member and said member being provided upon its upper face, adjacent one end, with a shoulder adapted to engage the outer edge of the adjacent base flange of the rail.

3. A rail anchor comprising a member adapted to extend beneath the base of a rail and jaws at the ends of said member for retaining said member on the base flanges of the rail, one of said jaws being movable on said member and said member being provided beneath said movable jaw with a raised shoulder adapted to engage the outer edge of the base flange of the rail.

4. A rail anchor comprising a member adapted to extend beneath the base flange

of a rail, said member being provided at one end with an integral jaw and being provided at its opposite end with a movable locking jaw, a tongue and groove connection between said member and said locking jaw and a shoulder formed adjacent the end of said member to engage the outer edge of the base flange of the rail.

5. A rail anchor comprising a member adapted to extend beneath the base flange of a rail, said member being provided at one end with an integral jaw and being provided at its opposite end with a movable locking jaw, a tongue and groove connection between said member and said locking jaw and a shoulder formed adjacent the end of said member to engage the outer edge of the base flange of the rail, said tongue and groove connection being inclined to cause said locking jaw to engage the base flange of the rail.

6. A rail anchor comprising a member adapted to extend beneath the base of a rail and project beyond both edges thereof and jaws at the ends of said member for retaining said member on the base flanges of the rail, one of said jaws being movable transversely of said member, a tongue and groove connection between said movable jaw and the adjacent projecting end of said member, and the projecting end of said member and said jaw being provided with oppositely disposed projections for holding the parts together.

7. A rail anchor comprising a member adapted to extend beneath the base of a rail and jaws at the ends of said member for retaining said member on the base flanges of the rail, one of said jaws being movable transversely of said member and being provided upon its end with a downwardly open groove, said member beneath said movable jaw having a raised rib to set within said groove and having a portion extending outwardly beyond said rib, said outwardly extending portion of said member and the outer portion of said jaw being provided with projections to interlock said parts.

8. A rail anchor comprising a member adapted to extend beneath the base of a rail and jaws at the ends of said member for engaging the base flanges of the rail, one of said jaws being movable transversely of said member and said member being provided at one end with oppositely inclined means for interlocking with the said movable jaw.

9. A rail anchor comprising a member adapted to extend beneath the base of a rail and jaws at the ends of said member for engaging the base flanges of the rail, said member being provided at one end with oppositely inclined ribs to receive the movable locking jaw of the rail anchor.

10. A rail anchor comprising a member adapted to extend beneath the base of a rail and jaws at the ends of said member for engaging the base flanges of the rail, one of said jaws being movable transversely of said member and said member being provided with raised ribs reversely inclined from the center toward the outer ends of said member and said movable jaw having its outer portion provided with a bendable ¹⁰ lug to engage with the adjacent part of said movable member.

WILLIAM M. MITCHELL.
